UNITED STATES PATENT OFFICE

2,035,710

REFRIGERATION APPARATUS

George A. Leyner and Anthony H. Kelly, Springfield, Mass., assignors to Westinghouse Electric & Manufacturing Company, East Pittsburgh, Pa., a corporation of Pennsylvania

Application April 26, 1934, Serial No. 722,414
Renewed September 6, 1935

6 Claims. (Cl. 62—126)

Our invention relates to refrigeration apparatus and particularly to the cooling element associated with mechanical refrigeration apparatus.

It is an object of our invention to provide an improved evaporator or cooling element construction wherein the return of only saturated or superheated refrigerant vapor and lubricant to the compressor is ensured.

It is a further object of our invention to provide an improved evaporator and baffle means therein.

It is another object of our invention to construct an evaporator suitable for use with a refrigerant and lubricant which mix in large proportions to form a substantially homogeneous mixture and which evaporator construction ensures return of only saturated or superheated gas and lubricant.

The refrigerant and lubricant in the evaporator, whether it forms a homogeneous mixture or not, is hereinafter termed "working fluid".

These and other objects are effected by our invention, as will be apparent from the following description and claims taken in connection with the accompanying drawing, forming a part of this application, in which:

Fig. 1 is a view of a refrigerating system including an evaporator with parts thereof broken away to show two embodiments of my improved baffle means;

Fig. 2 is a detail front view of the baffle means shown in the left-hand header of the evaporator shown in Fig. 1; and,

Fig. 3 is a detail front view of the baffle means shown in the right-hand header of the evaporator shown in Fig. 1.

Referring specifically to the drawing for a detailed description of our invention, numeral 1 designates a hermetically-sealed, refrigerant and lubricant containing motor-compressor unit which is preferably adapted to operate with a refrigerant and liquid which mix in substantially all proportions of substantially the range of pressures and temperatures encountered in the refrigerating system. The motor-compressor unit 1 withdraws working fluid through conduit 2 from an evaporator 3, and, after compressing it, forces the working fluid to a condenser 4 wherein the high pressure vapor is cooled by a fan 5, thereby condensing the working fluid. Condensed working fluid is then conveyed to a distributing device 6, such as, for example, a float valve, and from thence is conveyed to the evaporator 3 through an inlet conduit 7.

The evaporator 3 is preferably of the U-shaped

corrugated sheet metal type having a header 8 at one upper extremity of the U formation, a header 9 at the other end of the U-formation. Apertures 8a and 9a are formed in headers 8 and 9, respectively, and a cross header 11 connects the apertures 8a and 9a. The suction conduit 2 is connected in the cross header 11. The inlet conduit 7 preferably enters one of the headers and extends through a corrugation to the bottom of the evaporator 3 as fully described and claimed in the copending application of Jens Touborg, filed May 15, 1934, Serial No. 725,723, for Refrigeration apparatus and method of manufacture, and assigned to the assignee of the present application. 15

The level of working fluid in the evaporator 3 is shown in Fig. 1 and is preferably below the level of the openings 8a and 9a. Baffles 12 and 13 are preferably welded into the cross header 11 as shown in Fig. 1. When the working fluid in evaporator 3 is vaporized due to the heat from the refrigerator box and the low suction pressure prevailing in the evaporator 3, the baffles prevent the withdrawal of liquid working fluid through the cross header 11 and suction outlet 25 conduit 2 because any liquid contained in the vapor impinges upon the baffle and drops back into the liquid working fluid below the headers 8 and 9. If liquid working fluid is withdrawn, its refrigerating effect is lost for cooling the 30 evaporator 3 and inefficient operation of the refrigerating system results. Only saturated or superheated vapor, containing small quantities of lubricant, is therefore withdrawn from the evaporator 3. 35

The baffles 12 and 13 are shown as of different construction, but it is obvious that baffles of the same construction are preferably used in the evaporator 3. Baffle 12 is formed of a sheet metal disc 14 having upwardly extending louvers 15 40 formed therein. Baffle 13 is likewise formed of a sheet metal disc 16 having slots 17 formed therein.

From the foregoing, it will be apparent that we have provided an improved evaporator and baffle construction which ensures the return of only saturated or superheated vapor and lubricant to the compressor and which is adaptable for use in a refrigerating system utilizing a refrigerant and lubricant which form a substantially homogeneous mechanically inseparable mixture, as well as in a system utilizing a refrigerant and lubricant which stratify. 45

While we have shown our invention in two forms, it will be obvious to those skilled in the 55

art that it is not so limited, but is susceptible of various other changes and modifications, without departing from the spirit thereof, and we desire, therefore, that only such limitations shall 5 be placed thereupon as are imposed by the prior art or as are specifically set forth in the appended claims.

What we claim is:

1. An evaporator for a mechanical refrigerating system comprising two vertically-extending working fluid containing side walls, headers formed at the upper ends of the side walls, a cross-header connecting the side wall headers and having working fluid outlet means therein and baffle means disposed in the cross-header between the outlet means and the working fluid in the side walls.
2. An evaporator for a mechanical refrigerating system comprising two vertically extending working fluid containing side walls, headers formed at the upper ends of the side walls and having openings therein, a cross-header connecting the side wall header openings and having working fluid outlet means therein, and baffle means disposed in the cross-header between the outlet means and the working fluid in the side walls.
3. An evaporator for a mechanical refrigerating system comprising two vertically-extending working fluid containing side walls, headers formed at the upper ends of the side walls, a cross-header connecting the side wall headers and having working fluid outlet means therein and a plurality of baffles disposed adjacent the cross-header between the outlet means and the

working fluid in the side walls, said baffles being formed of members having louvers therein.

4. An evaporator for a mechanical refrigerating system comprising two vertically-extending working fluid containing side walls, headers formed at the upper ends of the side walls, a cross-header connecting the upper side wall header and having working fluid outlet means therein and a plurality of baffles disposed adjacent the cross-header between the outlet means and the working fluid in the side walls, said baffles being formed of members having upwardly extending louvers therein.

5. An evaporator for a mechanical refrigerating system comprising two vertically extending working fluid containing side walls, headers formed at the upper ends of the side walls, a cross-header connecting the side wall headers and having working fluid outlet means therein and a plurality of baffles disposed adjacent the cross-header between the outlet means and the working fluid in the side walls, said baffles being formed of members having slots therein.

6. An evaporator for a mechanical refrigerating system comprising two vertically extending working fluid containing side walls, headers formed at the upper ends of the side walls, a cross-header connecting the side wall headers and having working fluid outlet means therein and a plurality of baffles disposed adjacent the cross-header between the outlet means and the working fluid in the side walls, said baffles being formed of members having restricted openings therein.

art that it is not so limited, but is susceptible of various other changes and modifications, without departing from the spirit thereof, and we desire, therefore, that only such limitations shall 5 be placed thereupon as are imposed by the prior art or as are specifically set forth in the appended claims.

What we claim is:

1. An evaporator for a mechanical refrigerating system comprising two vertically-extending working fluid containing side walls, headers formed at the upper ends of the side walls, a cross-header connecting the side wall headers and having working fluid outlet means therein and baffle means disposed in the cross-header between the outlet means and the working fluid in the side walls.
2. An evaporator for a mechanical refrigerating system comprising two vertically extending working fluid containing side walls, headers formed at the upper ends of the side walls and having openings therein, a cross-header connecting the side wall header openings and having working fluid outlet means therein, and baffle means disposed in the cross-header between the outlet means and the working fluid in the side walls.
3. An evaporator for a mechanical refrigerating system comprising two vertically-extending working fluid containing side walls, headers formed at the upper ends of the side walls, a cross-header connecting the side wall headers and having working fluid outlet means therein and a plurality of baffles disposed adjacent the cross-header between the outlet means and the

working fluid in the side walls, said baffles being formed of members having louvers therein.

4. An evaporator for a mechanical refrigerating system comprising two vertically-extending working fluid containing side walls, headers formed at the upper ends of the side walls, a cross-header connecting the upper side wall header and having working fluid outlet means therein and a plurality of baffles disposed adjacent the cross-header between the outlet means and the working fluid in the side walls, said baffles being formed of members having upwardly extending louvers therein.

5. An evaporator for a mechanical refrigerating system comprising two vertically extending working fluid containing side walls, headers formed at the upper ends of the side walls, a cross-header connecting the side wall headers and having working fluid outlet means therein and a plurality of baffles disposed adjacent the cross-header between the outlet means and the working fluid in the side walls, said baffles being formed of members having slots therein.

6. An evaporator for a mechanical refrigerating system comprising two vertically extending working fluid containing side walls, headers formed at the upper ends of the side walls, a cross-header connecting the side wall headers and having working fluid outlet means therein and a plurality of baffles disposed adjacent the cross-header between the outlet means and the working fluid in the side walls, said baffles being formed of members having restricted openings therein.
